UNITED STATES PATENT OFFICE.

HOWARD E. MARSH, OF LOMPOC, CALIFORNIA.

QUARRY BLOCK-SAWING MACHINE.

Application filed September 24, 1924. Serial No. 739,606.

The present invention relates to a method of and apparatus for cutting bricks or blocks from a main body, such as a natural deposit or bed of kieselguhr, or other material, and an important object of the invention is to cut the blocks or bricks by the continuous operation of a single machine over-
coming the necessity of making the vertical cuts in the body by a separate machine or by an apparatus which is thrown into opera-
tive relation when the under cut and cut-off cuts are made.

A further object of the invention is to dispense with the mechanical control of the adjustment of the various parts of an apparatus for this purpose and to provide fluid pressure control means operated at little cost, by the use of which the adjustable parts of the mechanism are adapted for positive movement to the desired position. Another object is to provide a means for operating the cutting mechanism to make the vertical cuts in such manner as not to interfere with the continuous advancement of the mechanism for making the cut-off and the under cuts and to accomplish these results I have designed a form of mechanism, one embodiment of which is illustrated in the accompanying drawings, it being understood that changes and variations in the method, within the scope of the claims contained in the patent when issued, may be resorted to without departing from the spirit of the invention.

Referring to the accompanying drawings,—

Fig. 1 is a view in plan of one form of apparatus.

Fig. 2 is a view in side elevation, the mechanisms for cutting the vertical kerfs being omitted.

Fig. 3 is a sectional view of one of the fluid chambers illustrating a piston therein.

Fig. 4 is a view in detail elevation of the means for maintaining the horizontally reciprocatting member in adjusted position.

Fig. 5 is a view similar to Fig. 4 illustrating the mechanism for retaining the vertically reciprocatting member in adjusted position.

Fig. 6 is a view in longitudinal section of the slip joint conductor for conveying fluid to the vertical piston.

Fig. 7 is a diagrammatic view illustrating a tier of bricks formed by the use of the present invention.

Fig. 8 is a view in detailed elevation of the operating means for imparting vertical and horizontal movement to the vertical cutting member. 60

Fig. 9 is a vertical sectional view on line 9—9 of Fig. 8.

Fig. 10 is a view in plan of the mechanism illustrated in Figs. 8 and 9.

Fig. 11 is a view in detailed elevation of one of the cam grooves for controlling the vertical movement of the vertical cutting member. 65

Fig. 12 is a view in top plan of the construction illustrated in Fig. 11, illustrating 70 the removable member containing the cam groove.

Fig. 12^a is an enlarged longitudinal view of the grooved cylinder for imparting longitudinal movement to the vertical cutting 75 member relative to movement of the main supporting frame, the slide also being shown in the groove.

Fig. 13 is a view in detailed front elevation illustrating particularly the drive 80 means for the under cut and cut-off members, taken on line 13—13 of Fig. 15, one of the vertical kerf-cutting mechanisms being entirely omitted.

Fig. 14 is a vertical sectional view taken 85 on line 14—14 of Fig. 13.

Fig. 15 is a plan view of the construction illustrated in Fig. 13.

Fig. 16 is a view in end elevation of the construction illustrated in Fig. 15. 90

Fig. 17 is a view in detail illustrating the method of mounting one of the cutting members and

Fig. 18 is a view in detailed section of 95 one of the shaft bearings.

Fig. 19 is a view in vertical section of the vertically reciprocatting piston.

Fig. 20 is a view in detail section of the drive mechanism taken on line 20—20 of Fig. 1. 100

Fig. 21 is a vertical sectional view of the drive mechanism taken on line 31—31, Fig. 1.

Fig. 22 is a horizontal sectional view with the drive mechanism illustrated in Fig. 1, 105 taken on line 22—22 of Fig. 21.

Referring to the drawings, the apparatus illustrated comprises a vehicle body 1 mounted on wheels 2 arranged in pairs at opposite sides thereof and carried on the respective shafts 3. The wheels operate on tracks 4 and a pair of thrust wheels 5 oper-

ate on a separate track 6, one of the wheels preferably the rear wheel of each pair of wheels 2, and the respective thrust wheels 5 being of the flanged type. In propelling 5 the body over the rails, suitable drive mechanism is carried by the body and the same is conventionally illustrated in the form of an electric motor 6' connected through a chain drive 7 with a counter shaft 8, the 10 latter in turn carrying on its ends worms 9 intermeshing with the respective worm gears 10, one on each shaft 3.

The mechanism for carrying the cutting elements is illustrated as consisting of a 15 parallel disposed pair of frame members 11, preferably of cylindrical formation carried by and extending outwardly from the body 1 as in the drawing, the same being braced by truss rods 12 passing over struts 13', extending 20 upwardly from the forward portion of the body 1. The horizontal frame members 11 mount a tubular cross head 12', which is slidable longitudinally thereof and said cross head serves as a support and guide for a pair 25 of tubular vertically disposed frame members 13, which are vertically slidable through guide openings in the cross head. In the operation of the apparatus it is essential that the cross head 12' be moved to any 30 desirable position throughout the length of the members 11 and to accomplish this I illustrate a hydraulic mechanism consisting of a cylinder 14 carried by the body 1 and disposed parallel with the members 11 and 35 within the same operates a piston 15 connected at its outer end with the cross head 12'. Fluid pipes 16 extending from a valve casing 17 convey fluid under pressure into the cylinder 14 on opposite sides of the piston, dependent on the position of the 40 controlling valve 18. Fluid under pressure is admitted into the valve casing 17 through pipe 19, leading from a fluid containing pressure tank 20 mounting an expansion 45 dome 21. A pipe 22 leading from a pump 23 operated by a motor 24 supplies fluid under pressure from a container 25 to the tank 20 and the operation of the pump maintains the fluid under the desired working 50 pressure. Dependent on the position of the valve 18 the pipes 16 are alternately converted into pressure and relief pipes dependent on the direction of operation of the piston 15 and under all conditions when one 55 pipe is applied as a pressure the other is utilized as a relief pipe and the fluid passing therethrough is discharged into the container 25. It is desirable to releasably lock the cross head 12' in its adjusted position 60 on the frame members 11 and to accomplish this I provide a notched locking rod 26 extending from the body 1, passing over the cross head 12' and supported at its outer end on the member 27' which connects 65 the free ends of the frame members 11. A

slotted lock casing 27 is carried by the cross head 12' and through the same extends the member 26, the lock casing 27 carrying a locking pin 28 adapted for selective reception within the member 26 throughout its 70 length.

The vertically disposed tubular members 13 are connected at their lower end by a cutter supporting frame 29 and to reciprocate the same in unison within the cross head 12' 75 I provide a piston 30, the rod of which connects with the member 29 and said piston reciprocates within a vertically disposed cylinder 31, carried by the cross head 12' between the members 13. To relatively lock 80 the frame 29 at the desired height, I employ a duplicate of the construction described above for releasably locking the cross-head 12' in position on the frame members 11, and I designate the duplicated elements by 85 the same reference characters with the addition of a prime mark. The notched rod 26' connects at its lower end with the frame 29 and at its upper end to the upper end of one of the vertical frame members 13. To 90 admit fluid under pressure to the opposite ends of the cylinder 31 to raise or lower the piston 30 therein, I connect with the opposite ends of the cylinder fluid conducting pipes 32, a portion of each of which extends 95 parallel with the rod or piston 15 and said pipes are slidably mounted within larger fixed pipes 33 through glands 34, the first pipes being carried by the body 1 and the pipes 32 being mounted to move with the 100 cross head 12'. The pipes 33 connect with the valve casing 34' within which is mounted a valve 35, said casing being supplied with fluid under pressure from tank 20 by a pipe 36, a relief pipe 37 extending from the valve 105 casing 34' and discharging into the container 25. The position of the valve 35 when in the casing 34' controls the passage of fluid through pipes 32 and 33 and causes a raising or lowering of the piston 30 within the cylinder 31. The above described mechanism 110 controls the horizontal movement of the cross head 12' and the vertical adjustment of the cutter mounting frame 29 and the movements of these respective parts are controlled by the respective valves 18 and 35, operatable independently of each other and the fluid employed, when relieved from the 115 respective cylinders 31 and 14, returning to the container 25, forms a self-contained 120 hydraulic system carried on the vehicle body 1.

In the present embodiment of the invention reference being had particularly to Figs. 1, 13 and 15 of the drawings, I carry 125 on the cutter supporting frame mechanism for simultaneously making successive vertical cuts in the face of the body and continuous under cuts and cut off cuts, all operated at the same time and capable of functioning 130

when the vehicle 1 is moved in either direction on rails 4.

is mounted in connection with only one mechanism, that mechanism being the one at the head end of frame 29, depending on its direction of travel.

The embodiment of the undercut and cut off mechanism which I will first describe, and which is particularly illustrated in Figs. 13 to 15 inclusive, consists of a pair of horizontally disposed rotatably mounted shafts 38, positioned below the supporting frame 29, one preferably beneath each guide 13 at right angles to the frame 29. Detachably secured to the projecting end of one of said shafts, dependent on the direction of movement of the body 1, is positioned a cut-off saw or member 39, the same being held to its respective shaft by attaching screws 40 having threaded engagement with a propeller 41 held to the end of the shaft by a screw coupling 42. Only one saw 39 is employed, it being mounted on whichever shaft 38 is the rear shaft of the pair, depending on the direction of movement of the body 1. The shafts carry on their opposite ends sprockets 40 over which passes an endless chain 41, the chain operating over the sprockets 42 and 43 mounted on the respective shafts 44 and 45. A take-up member 46 of any suitable construction maintains the chain 41 taut and a housing 47 encloses the chain. The shafts 38 constitute the armature shafts of suitable reversible electric motors 47 for imparting rotation to the armatures mounted on said shafts, electricity being derived from any suitable source of supply. The shaft 45, Figs. 13 and 14, extends through a gear casing 48 disposed centrally beneath the frame 49 and drives through the beveled gear mechanism 49 a vertically disposed rotatable shaft 50 depending from the under side of the frame 29. The shaft 50 removably mounts any desired number of under cut saws 51, disposed in parallel horizontal planes at right angles to the cut-off saw 39, the periphery of the under cut saws intersecting a plane parallel with that of the cut off saw as illustrated in Figs. 14 and 15. Thus it will be apparent that saws 51 and cut-off saw 39 are driven in the same direction at the same speed and in the operation of the apparatus the under cut saws at all times travel in advance of the cut-off saw.

at the head end of frame 29, depending on its direction of travel.

This mechanism is particularly illustrated in Figs. 8 to 12 inclusive and the embodiment illustrated is constructed as follows, the mechanism at each end of the frame being the same, a description of one will suffice. Disposed parallel with one of the axles 3 between the side of the vehicle body and the axle and rotatable in a bearing 52, Fig. 1, is a shaft 53, Figs. 1 and 20, longitudinally slotted as at 54 and on which is feathered the sprocket 55, held from longitudinal movement in the bearing 52. Power is transmitted to the sprocket 55 by a chain 56 driven from the axle 3 mounting a sprocket 57. This mechanism forms a part of the drive means for the cutting mechanism, which provides a vertical kerf and the forward end of the shaft 53 rotates in a transverse support 58 movable longitudinally with the cross head 12. The shaft 53 transmits power through a chain 9, beveled gear mechanisms 60 and 61 to a shaft 62 disposed parallel with and slightly in rear of the cutter support 29 as illustrated in the drawings, the latter shaft being supported at its ends in bearings 63. This shaft 62 forms a power shaft for transmitting the final drive through a chain mechanism 64 to the cutter for forming the vertical kerf in the face of the bank. To provide an uninterrupted drive between the beveled gear mechanism 60, movable longitudinally with the frame members 11 and the beveled gear mechanism 61, movable vertically with the cutter supporting frame head 29, the shaft 65 is feathered within the horizontal gear member of the beveled gear connection 60 as clearly illustrated in Figs. 21 and 22. Each end of the cutter supporting frame 29 supports a substantially U-shaped frame 66 in which is journaled the shaft 67, driven by the chain drive connection 64. The shaft 67 supports a cylinder 68 thereon, formed with a cam groove 69, Fig. 12^a, the major portion of which extends spirally therearound and the terminals of the spiral being connected by a uniting channel 70.

The mechanism for forming the vertical kerfs in the face of the body in advance of the travel of the under cut and cut-off saws is operated in timed relation with the travel of the body 1 and the mechanism for operating and mounting the saw for forming this series of vertical kerfs is duplicated at each end of the frame 29 as illustrated in Fig. 1. To conserve space, I have illustrated, in

Figs. 13 and 15, this mechanism as carried at one end of the frame 29, but it is to be understood that in actual construction this mechanism is carried at both ends of the frame 29. In operation, a cutting means

This formation is to maintain the herein after described carriage arrested from longitudinal movement over the face of the member to be cut during the formation of the vertical kerf and to advance the same in the direction of travel of the main frame at a speed twice as great as that at which the main vehicle or carriage travels. Parallel guide rods 71 carried by the frame 66 are disposed in alignment at opposite sides of the shaft 67, and the same provide guides for reciprocating frame 72, slidably mounted thereon, the arm 73 of which extends transversely across the shaft 67 above cam cylinder 120 125 130

der 68. The arm 73 carries a slide 74 operating in the groove 69; thus, on the rotation of shaft 67, movement of the carriage 72 longitudinally of the member 71 will be effected and its reciprocation will be maintained in timed cycles, in timed relation with the movement of the main vehicle body 1 in either direction. The frame 72 carries a pivoted arm 75 overlying the cylinder 68 and the same is connected at its end through a slotted fulcrum 76 with a vertically disposed reciprocating arm 77 movable through a guide 78 and on its lower end carrying a motor 79 conventionally illustrated, the armature shaft of the motor supporting a saw 80 for forming the vertical kerf in the face of the natural deposit. With the pivoted arm 75 is pivotally connected an operating arm 81, its lower end supporting guide pins 82 receivable within the cam guides 83 formed in the opposite faces of the removable block 84 carried by a main plate 85. The longitudinal movement of the frame 72 on guides 71 caused by the rotation of the cylinder 68 causes a relative movement of the pins 82 in the cam guide 83, and this operation causes the vertical reciprocation of the member 80 to form a vertical kerf in the face of the natural deposit. Thus it will be observed that the cam groove 69 with its connecting member 70 controls the movement of the cutting member 80 in the direction of movement of the main carriage and the cam groove 83 controls the vertical movement of the cutting member 80 in the direction at right angles with the movement of the main carriage. It will be observed that the member 84 is removable from the main supporting plate 85, this admitting of the employment of grooved plates wherein the groove is of any desired pitch to vary the vertical throw of the cutting member 80 whereby the same will cut a depth corresponding with the thickness of one or a number of bricks, the cam groove 83 illustrated being of a throw only sufficient to cut one brick. At the commencement of the operation of the kerf forming members in the face of the natural deposit to cut successive tiers of bricks or blocks therefrom, it is desirable to have the vertical kerfs of succeeding tiers or layers register, and to facilitate this registering without varying the operation of the machine or changing its position I provide a micrometer adjustment for moving the cutting member 80 independent of the end of the frame 29 and to accomplish this employ a micrometer screw 86 carried by a stationary member 87 and cooperating with the plate 85, this adjustment moving the plate 85 to and from the plate 87, which movement carries the cylinder 68 therewith, lineal movement of the cylinder relative to shaft 67 being accomplished by the sliding connection 88, Fig. 12^a, between the cylinder

shaft and the shaft 67. The construction and operation of the invention will be understood from the foregoing description and the operation, in brief, is as follows:

Assuming that the face of the formation that is to be operated on extends at a right angle to the plane of the saw 80 at the top of Fig. 1 and that vertical kerfs have been already cut by the saw 80 in the upper face of that part of the formation extending from the saw 80 to the saws 51, the frame 1 will be driven forward, or toward the top of the sheet containing Fig. 1, thus causing the saws 51 to continuously operate to cut horizontal kerfs intersecting the vertical kerfs previously made by the saw 80. Assuming that the saw 80 has just been retracted out of the last kerf that it has cut, the pins 82 will ride in the horizontal limb of the cam grooves 83, thus maintaining the saw 80 in retracted position for an interval of time. During this interval of time the slide 74 will ride in the channel 70, thus causing the frame 72 to travel in the same direction as the frame 1 and sufficiently faster than said frame 1 to position the saw 80 the length of a block ahead of its last kerf. Then the pins 82 will ride in the descending limb of the cam grooves 83 to cause the saw 80 to make another cut and while said saw 80 is making its cut, the groove 69 will engage the slide 74, thus causing the frame 72 to travel at the same speed as the frame 1, but in the opposite direction so that the saw 80 will not be subjected to translation relative to the formation while said saw is making its cut. At the finish of the cut, the pins 82 will ride in the ascending limb of the cam grooves 83 to cause the saw 80 to be retracted from the cut and this occurs while the slide 74 is in the groove 69 so that translation of the saw 80 relative to the formation does not occur while the saw 80 is being retracted. The cycle just described is then repeated indefinitely until one end of the area being operated on is reached. This completes the cutting of one tier of blocks. The saw 80 will then be removed from the armature shaft on which it is mounted and said saw will be secured to the armature shaft of the other motor 79, and the saw 39 will be changed in the other shaft 38. Then the operator will properly manipulate the valve 35 to lower the cutter-supporting frame 29 sufficiently to bring the saws into position for cutting another tier of blocks, and the frame 1 will be driven in the reverse direction to cut another tier of blocks. The apparatus will be thus adjusted at each end of the travel of the frame 1 and successive tiers of blocks cut to the lowest level to which the saw-supporting frame 29 can be lowered, thus cutting off a complete layer of the formation into blocks. The operator will then properly manipulate the valves 18, 35 to

bring the saws into position for operating along the upper face of the formation and, thus, successive layers of the formation are cut into blocks. The cut blocks will be removed as rapidly as they are cut so that the to and fro motion of the saws along the face of the formation will not be interfered with.

I claim:

1. An apparatus for cutting bricks or blocks from a bank of material, including a vehicle, guide means extending laterally therefrom, a cross head mounted to move longitudinally thereon, a cutter carrying means mounted to move vertically on said cross head, a cutter mechanism carried by said cutter head including a plurality of cutting members, hydraulic means carried by the vehicle for imparting independent movement to the cross head and cutter head carrying means to adjust the same relatively to each other, means for operating the carriage, and means for moving one of the cutting members in timed relation therewith.

2. An apparatus for cutting bricks or blocks from a bank of material, including a vehicle, guide means extending laterally therefrom, a cross head mounted to move longitudinally thereon, a cutter carrying means mounted to move vertically on said cross head, a cutter mechanism carried by said cutter head including a plurality of cutting members, one of said cutting members being positioned to cut transversely to the path of travel of the vehicle, hydraulic means carried by the vehicle for imparting independent movement to the cross head and cutter head carrying means to adjust the same relatively to each other, means for operating the carriage, means for moving the transversely cutting saw up and down and means for intermittently moving the last mentioned cutting member with the vehicle at an increase in speed over that of the vehicle when the last mentioned cutting member is up, and for moving said last mentioned cutting member in the opposite direction at the same speed as the vehicle when said last mentioned cutting member is moving down.

3. An apparatus for cutting bricks or blocks from a bank of material, including a vehicle, guide means extending laterally therefrom, a cross head mounted to move longitudinally thereon, a cutter carrying means mounted to move vertically on said cross head, a cutter mechanism carried by said cutter head, hydraulic means carried by the vehicle for imparting independent movement to the cross head and cutter head carrying means to adjust the same relatively to each other, means for operating the carriage, and means for operating one of said cutters in a plane at right angles to the direction of movement of the vehicle toward the same while the vehicle is travelling, and

means for moving the last mentioned cutter in a direction opposite to that of movement of the vehicle and at the same speed as said movement while said last mentioned cutter is making its cutting operation.

4. An apparatus for cutting blocks or bricks from a bank of material comprising a vehicle, means for moving the same relatively to the face of the bank, saw means carried thereby and movable vertically of the bank face to form successive vertical parallel kerfs therein, means for causing a reciprocating movement in a vertical plane of said saw means, and means for causing a movement of said saw means in the direction of travel of the vehicle and at a speed greater than that of the vehicle when the said saw means is at the upper end of its vertical movement, and for causing said saw means to move in the opposite direction to that of the vehicle at the same speed as said vehicle when said saw means is moving from its upper position to its lower position.

5. An apparatus for cutting blocks or bricks from a bank of material comprising a vehicle, means for moving the same relatively to the face of the bank, saw means carried thereby and movable vertically of the bank face to form successive vertical parallel kerfs therein, means for causing a reciprocating movement in a vertical plane of said saw means, means for causing a movement of said saw means in the direction of travel of the vehicle and at a speed greater than that of the vehicle when the said saw means is at the upper end of its vertical movement, and for causing said saw means to move in the opposite direction to that of the vehicle at the same speed as said vehicle when said saw means is moving from its upper position to its lower position, and a driving connection between the saw moving means and the vehicle moving means.

6. An apparatus for cutting bricks or blocks from a bank of material including a vehicle, means for moving the same relatively to the face of the bank, saw means carried thereby for forming successive parallel vertically disposed kerfs in the face of the bank, means for operating the saw, and means operated in timed relation with the movement of the carriage for moving said saw means vertically and in a horizontal plane, its movement in the latter plane being in the direction of travel of the vehicle at a speed greater than that of the vehicle when the said saw means is at the upper end of its vertical movement, and for causing said saw means to move in the opposite direction to that of the vehicle at the same speed as said vehicle when said saw means is moving from its upper position to its lower position.

7. An apparatus for cutting bricks or blocks from a bank of material, including a

vehicle, means for moving the same relatively to the face of the bank, saw means carried thereby for forming successive parallel vertically disposed kerfs in the face 5 of the bank, means for operating the saw, and means operated in timed relation with the movement of the carriage for moving said saw means vertically and in a horizontal plane, and when the said saw means 10 is at the upper end of its vertical movement, and for causing said saw means to move in the opposite direction to that of the vehicle at the same speed as said vehicle when said 15 saw means is moving from its upper position to its lower position.

8. An apparatus for cutting bricks or

blocks from a bank of material comprising a vehicle, saw means carried thereby for forming successive parallel kerfs in the bank face, means for operating the saw means, 20 means for moving the saw in a vertical plane, and means for moving the saw in a substantially horizontal plane at one end of its vertical stroke and at a speed greater than that of the travel of the vehicle in the direction of said travel and to move said saw means in a plane in the opposite direction relative to the movement of the vehicle 25 at the same speed as said movement.

In testimony whereof I have signed my 30 name to this specification.

HOWARD E. MARSH.
